DESIGN FOR A CLAMP FOR ATTACHING
FIXTURES TO ROBE RAILS

James I. Hamm, Fairfield, Conn., assignor to The
Bridgeport Coach Lace Company, Incorporated,
Bridgeport, Conn., a corporation of Connecticut

Application May 1, 1935, Serial No. 56,639

Term of patent 3½ years

To all whom it may concern:

Be it known that I, James I. Hamm, a citizen of the United States, residing at Fairfield, county of Fairfield, State of Connecticut, have invented a new, original, and ornamental Design for Clamp for Attaching Fixtures to Robe Rails, of which the following is a specification, reference being had to the accompanying drawing, forming part thereof.

Fig. 1 is a side elevation of a clamp for attaching fixtures to robe rails;

Fig. 2 is a top plan view thereof; and

Fig. 3 is an end elevation looking from the right of Fig. 1.

I claim:

The ornamental design for a clamp for attaching fixtures to robe rails, substantially as shown.

JAMES I. HAMM.
